US00D504439S

(12) **United States Design Patent** (10) Patent No.: **US D504,439 S**
(45) Date of Patent: **** Apr. 26, 2005**

(54) **FACSIMILE MACHINE**

(75) Inventor: **Shigeharu Katayama, Kakamigahara (JP)**

(73) Assignee: **Brother Industries, Ltd., Nagoya (JP)**

(**) Term: **14 Years**

(21) Appl. No.: **29/204,943**

(22) Filed: **May 7, 2004**

(30) **Foreign Application Priority Data**

Nov. 13, 2003 (JP) 2003-033908

(51) LOC (7) Cl. **16-03**

(52) U.S. Cl. **D14/467**

(58) Field of Search D14/462-471; 358/400, 401; D18/36, 37
